DROP-OUT FUSE DEVICE

William O. Schultz, South Milwaukee, Wis., assignor to Line Material Company, South Milwaukee, Wis., a corporation of Delaware

Application September 22, 1941, Serial No. 411,812

21 Claims. (Cl. 200—114)

This invention relates to a drop-out fuse device.

Objects of this invention are to provide a novel form of fuse, preferably a housed type of expulsion fuse for example, in which the fuse tube is biased downwardly and is slidably guided and is normally restrained from such motion by the fuse link, but which upon blowing of the fuse link first acts in the manner of an expulsion fuse and thereafter moves downwardly and projects from the lower portion of the housing, thus increasing the gap in the circuit as the upper contact of the fuse tube moves away from the upper stationary contact carried by the housing.

Further objects are to provide a construction in which the lower fastening means or retaining lever for the fuse link is carried by the fuse tube itself and moves downwardly with the fuse tube when it is released by the rupturing of the fuse link, such lower retaining lever being biased toward outward motion and withdrawing any of the lower portion of the fuse link that may remain intact from the fuse tube in a quick and positive manner and also detaching itself from a stationary part of the device to which it was originally releasably attached.

Further objects of this invention are to provide a drop-out fuse construction in which the lower retaining member or lever which is carried by the fuse tube is electrically dead after the fuse blows and so that thereby any portion of the fuse link hanging therefrom is also electrically dead, thereby guarding against accidental hazards and yet giving a visual indication by the projecting portion of the fuse tube and associated parts that the fuse link has been ruptured.

Further objects are to provide a drop-out fuse construction in which main upper contact means are provided which include both a contact carried by the fuse tube and spaced downwardly from the upper end thereof and a stationary contact which carry the main current under normal conditions and thus locate what is sometimes called the "hot spot" at a point remote from the upper closure cap which clamps the upper end of the fuse link, latch means being also provided to hold the fuse tube in closed position and also to maintain contact during a portion of the downward sliding motion of the fuse tube, both the main contact members and the latch means urging the fuse tube downwardly in addition to the effect of gravity.

Further objects are to provide a drop-out fuse construction in which a housing is provided with

5 a pivotal door which carries a sleeve through which the fuse tube slides, a barrier being also carried from the door and preferably integral with the sleeve and extending substantially across the lower portion of the channel-shaped housing, to thereby separate the lower end of the fuse link and the open projecting end of the fuse tube from all other portions of the apparatus, to thereby prevent the entrance of gases upon the blowing of a fuse link from the main body of the housing, the barrier being spaced upwardly from the lower end of the housing and from the lower end of the door to provide a shelter for the lower end of the fuse tube, the retaining lever or fuse link extractor, and for the lower end of the fuse link under normal conditions.

10 In general this invention is an improvement over that disclosed in Patent No. 2,138,255 of November 29, 1938, for Fuse construction, issued to William O. Schultz and Alwin G. Steinmayer.

15 Embodiments of the invention are shown in the accompanying drawings, in which:

20 Figure 1 is a side elevation, partly in section, showing the fuse device in its operative position.

Figure 2 is a view from the bottom of Figure 1.

25 Figure 3 is a view with the door removed and with parts in section and broken away.

Figure 4 is a view looking down from the top 30 of the device with the top of the housing broken away.

Figure 5 is a sectional view on the line 5—5 of Figure 1.

35 Figure 6 is a sectional view on the line 6—6 of Figure 1.

Figure 7 is an enlarged fragmentary view, 40 partly in section, showing the device as it appears when the releasing lever or fuse link extractor has moved part way towards releasing position upon-rupture of the fuse link.

Figure 8 is a view looking into the housing from the front showing the upper end of the device with the door removed.

45 Figure 9 is a view, partly in section, showing the position of the parts after the fuse link has slid downwardly to its lowermost position.

Figure 10 is a fragmentary view of a further 50 form of the invention.

Referring to the drawings, it will be seen that the device comprises a channel-shaped housing 1 formed of insulating material and having an open front and an open lower end. This housing is normally closed by an insulating door 2. This door is provided with a metal guiding sleeve

3 which has an inwardly extending barrier 4 formed integrally therewith and extending transversely across the channel-shaped housing and spaced a distance from the lower end thereof. This barrier is provided with a pair of downwardly extending lugs 5 which carry a pivot pin 6. The pivot pin is received within a pair of hook members 7 which are cemented or otherwise secured in the rear wall of the housing.

The housing is also provided with an upper and a lower resilient stationary contact indicated at 8 and 9 respectively. The lower stationary contact 9 is provided with inwardly turned outwardly flaring end portions 10, see Figure 6, so that they will hook over the sides of the sleeve 3 and thus hold the door closed whether the fuse is in its uppermost or in its lowermost position, as will hereinafter be described.

The upper contact 8 is provided with a pair of resilient arms which have outwardly turned lower ends 11. The lower and upper contact are carried, respectively, by vertical plate like members 13 and 14 which have rearward extensions cemented or otherwise secured in the rear wall of the housing. These members are apertured and receive a pair of screws 15 which are threaded into conductor clamping plates 16 so that the line and load conductors leading through the apertures in the side walls of the housing may be clamped between the rear plates 16 and the forward plates 13 and 14 at any angle desired.

The upper plate 14 of the upper terminal structure also carries a U-shaped resilient latch 17 which has downwardly slanting inner faces and which has inwardly turned and outwardly flaring end portions 18, see Figure 4.

An insulating fuse tube 19 is slidably mounted within the sleeve 3 and is provided with an upper closure cap 20 of metal which clamps the upper buttonhead 21 of the fuse link. The fuse link is provided with a strain wire 22 and a fusible section 23 and a flexible leader 24. This fuse link is carried within the fuse tube and projects outwardly through the open lower end thereof.

The fuse tube is also provided with an upper contact which is indicated generally at 25 and is provided with a pair of upwardly slanting contact surfaces 26 on opposite sides thereof which engage the outwardly turned portions 11 of the upper resilient stationary contact 8, see Figure 3.

The upper closure cap 20 is normally engaged and held by the upper resilient latch 17, as shown in Figures 1, 3 and 4. It is to be noted that the upper stationary resilient contact 8 has a cam action with the slanting faces 26 of the upper contact of the fuse tube and urges the fuse tube downwardly. In addition to this, it is to be noted that the upper resilient latch 17 urges the fuse tube downwardly. These two forces are in addition to the action of gravity which also urges the fuse tube downwardly.

If desired the door 2 may be provided with an inwardly projecting finger 25', see Figures 1 and 5, which fits within a recessed portion of the upper contact 25 of the fuse tube so that when the door is moved towards closed position, excessive strain is not placed on the sleeve 3 but instead the upper end of the fuse tube is pushed into place by the finger 25' of the door 2. Also it is to be noted, particularly from Figures 1 and 5, that the rear faces of the outwardly projecting portions of the upper contact 25 are slanting so as to facilitate spreading of the arms of the upper resilient contact 8 when the fuse tube is rocked into closed position.

The fuse tube is provided with a collar 27 adjacent and spaced from its lower end. This collar is provided with a rearwardly projecting rigid arm 28 to which is pivotally mounted the fuse link extracting lever 29. This fuse link extracting lever is also the means for holding the fuse tube in its uppermost position as long as the fuse link is unruptured and for releasing the fuse tube upon rupture of the fuse link while also acting as a fuse link extractor.

The fuse link extractor 29, it will be seen from Figures 1, 7 and 9, is pivoted intermediate its ends to the lower end of the arm 28 rigid with the collar 27 carried by the fuse tube 19. Its rear end is hook-shaped as indicated at 30 and normally hooks over the pivot pin 6. The fuse link extractor extends forwardly and is spaced to the side of one side of the fuse tube, the fuse tube being preferably provided with a flat face 31, see Figures 3 and 9, adjacent the fuse link extractor.

This fuse link extractor is provided with a fuse link clamping thumb screw 32 which is threaded on a stud 33 carried by the fuse link extractor 29 and which serves to clamp the leader 24 of the fuse link, as shown in Figures 2 and 3. This fuse link extractor 29 is provided with a notched lower portion 34 within which the transversely bent portion of the fuse link is positioned and it is also provided with a laterally projecting boss 35 behind which the extreme end of the leader 24 of the fuse link is positioned, as shown most clearly in Figures 1 and 3.

When the fuse link is intact and the door 2 is rocked to closed position, the upper latch engages the upper closure cap 20 of the fuse tube and the upper resilient stationary contact 8 has its arms slightly sprung apart and engages the slanting contact surfaces 26 of the upper contact 25 of the fuse tube, see Figure 3, and the arms of the lower resilient stationary contact 9 engage the flat opposed contact faces 36 formed on the sleeve 3, as shown most clearly in Figure 6, the inwardly turned ends 10 hooking in front of the outwardly projecting lateral portions of the sleeve 3.

It is to be noted that the upper resilient stationary contact 8 has a relatively high bearing pressure against the contact surfaces 26 of the upper contact 25 of the fuse tube and thus what is usually termed the "hot spot" is removed from the upper closure cap of the fuse tube. Though the upper closure cap of the fuse tube is metal and contacts with the resilient metal arms 17 of the latch, nevertheless the major current flow passes through the main upper contact members 25 and 8, see Figure 3, and relatively small current passes from the closure cap 20 to the latch arms 17. It may be desirable, as has been shown in the drawing, to provide a laminated structure for the upper and lower resilient stationary contacts 8 and 9. The inner arms of these contacts may be most highly conducting and the outer arms may be more resilient and assist in furnishing the spring pressure to insure adequate contact, or, if desired, both of the members forming the laminated structure in each of the upper and lower stationary contacts may be of the same material.

When an overload occurs and the fuse link is ruptured, the fuse tube is released and moves downwardly as the combined fuse link extractor and fuse tube retaining member 29 rocks about its intermediate pivot point 37, see Figures 1 and 7, and the hook like portion 30 of the fuse link

extractor moves away from the pivot pin 6 and thus completely releases the fuse tube. The fuse tube moves downwardly and carries with it the fuse link extractor so that the fuse link extractor, as well as any remaining unburned portion of the fuse link, are electrically dead after rupture of the fuse link and after the fuse tube has moved to its lowermost position, as shown in Figure 9.

It is to be noted that the resilient upper stationary contact 8 maintains contact with the upper contact 25 of the fuse tube for a brief interval during the downward sliding motion and the upper resilient latch arms 17 maintain contact with the closure cap for a longer period during the downward sliding motion of the fuse tube to thereby insure complete rupture of the circuit within the fuse tube prior to the breaking of contact between the upper end of the fuse tube and the upper terminal.

The door remains closed after the fuse tube has slid downwardly to its lowermost position, as shown in Figure 9, due to the interengagement between the lower stationary contact 9 and the sleeve 3, as shown most clearly in Figure 6.

In the form of the invention shown in Figure 10, a slightly different manner of securing the cam action between the resilient stationary upper contacts and the upper main contact of the fuse tube is provided. This is secured by having the upper stationary resilient contact 39 provided with flat upwardly slanting arms which engage protuberances 40 extending outwardly from opposite sides of the main upper contact 41 of the fuse tube. It is apparent that a cam action is obtained by this construction which acts to produce a downward thrust on the fuse tube.

It will be seen that a novel form of drop-out fuse device has been provided in which the relatively "hot spot" is removed from the closure cap, and it will be seen further that the construction is such that a transverse barrier carried rigidly by the door and preferably integral with the sleeve has been provided which extends transversely across the channel-shaped housing and serves to divide the housing off below the lower stationary contact so that the fuse link extractor, the open end of the fuse tube, and the lower end of the fuse link are all located below the barrier.

In this way there is very little chance of any conducting gases flashing back into the body of the housing. If desired, this effect may be somewhat enhanced by providing a transverse connecting web 38 which joins the hook like members 7 and which extends transversely across slightly above the inner end of the barrier 4, as shown most clearly in Figure 2.

By having the barrier spaced upwardly a slight distance from the lower end of the channel-shaped housing, it will be seen from Figures 1 and 3 particularly, that a small individual compartment is provided for the fuse link extractor so that it is sheltered from snow and rain but nevertheless is separated off from the lower stationary contact or any other interior portion of the housing above the barrier.

In refusing the device, the fuse tube and door assembly may be unhooked from the hook member 7 and the fuse tube may be refused and thereafter the assembly may be again pivotally connected to the hooks 7 and the door and fuse tube assembly rocked back to closed position.

Although this invention has been described in considerable detail, it is to be understood that such description is intended as illustrative rather

than limiting, as the invention may be variously embodied and is to be interpreted as claimed.

I claim:

1. A drop-out fuse device having upper and lower stationary contacts, a downwardly biased fuse tube, guiding means for slidably guiding said fuse tube, a contact rigidly carried by said fuse tube adjacent the upper end thereof and having a slanting surface normally engaging the upper stationary contact, said upper stationary contact being resilient and producing a downward thrust on said fuse tube through the agency of the slanting surface of the contact of said fuse tube, said slanting surface acting like a cam and said resilient upper contact exerting a lateral pressure on said slanting surface, a fuse link within said fuse tube, means adjacent the upper end of said fuse tube and spaced from the contact of said fuse tube and separate and distinct from the contact of said fuse tube for locking the upper end of said fuse link, and means controlled by said fuse link and normally holding said fuse tube in its uppermost position and releasing said fuse tube upon rupture of said fuse link.
2. A drop-out fuse device having upper and lower stationary contacts, a downwardly biased fuse tube mounted for both downward and lateral motion, guiding means for slidably guiding said fuse tube, a contact carried by said fuse tube adjacent the upper end thereof and having a slanting surface normally engaging the upper stationary contact, said upper stationary contact being resilient and producing a downward thrust on said fuse tube through the agency of the slanting surface of the contact of said fuse tube, said slanting surface acting like a cam and said resilient upper contact exerting a lateral pressure on said slanting surface, a fuse link within said fuse tube, and a stationary latch distinct from said upper stationary contact for locking said fuse tube in place against lateral motion, and a fuse link extractor biased towards fuse link extracting motion and controlled by said fuse link and normally holding said fuse tube in its uppermost position and releasing said fuse tube upon rupture of said fuse link, said fuse link extractor being electrically dead when said fuse tube has slid downwardly.

3. A drop-out fuse device having upper and lower stationary contacts, a downwardly biased fuse tube mounted for both downward and lateral motion, guiding means for slidably guiding said fuse tube, a contact carried by said fuse tube adjacent the upper end thereof and cooperating with said upper stationary contact to form a pair of contacting elements, one of said contacting elements having a slanting surface and the upper stationary contact being resilient to produce a downward thrust on said fuse tube through the agency of said slanting surface, a stationary latch distinct from said upper stationary contact for holding said fuse tube against lateral motion, a fuse link within said fuse tube, the said slanting surface being engaged by the other contact and having a cam action to produce said thrust, and a fuse link extractor biased towards fuse link extracting motion and controlled by said fuse link and normally holding said fuse tube in its uppermost position and releasing said fuse tube upon rupture of said fuse link, said fuse link extractor being electrically dead when said fuse tube has slid downwardly.

4. A drop-out fuse device having upper and lower stationary contacts, a downwardly biased fuse tube mounted for both downward and lat-

eral motion, guiding means for slidably guiding said fuse tube, a contact carried by said fuse tube adjacent the upper end thereof and having upwardly slanting surfaces on opposite sides thereof, said upper stationary contact being resilient and having contact surfaces normally engaging the slanting surfaces of the contact of said fuse tube and being spread apart by the contact of said fuse tube and cooperating with said slanting surfaces to produce a cam action urging said fuse tube downwardly, a fuse link within said fuse tube normally electrically connecting the contact of said fuse tube and said lower stationary contact, a stationary latch distinct from said upper stationary contact for holding said fuse tube against lateral motion, and means controlled by said fuse link for normally holding said fuse tube in its uppermost position and releasing said fuse tube for downward sliding motion upon rupture of said fuse link, the means controlled by said fuse link being electrically dead when said fuse tube has slid downwardly.

5. A drop-out fuse device having upper and lower stationary contacts, a downwardly biased fuse tube, guiding means for slidably guiding said fuse tube, a contact rigidly carried by said fuse tube adjacent and spaced from the upper end thereof and having contact surfaces on opposite sides thereof, said upper stationary contact being resilient and having arms engaging the contact surfaces of the contact of said fuse tube and having a cam action therewith to produce a downward thrust on said fuse tube, a fuse link within said fuse tube normally electrically connecting the contact of said fuse tube and said lower stationary contact, a closure cap for clamping the upper end of said fuse link to the upper end of said fuse tube in spaced relation to the contact carried by the fuse tube, and means controlled by said fuse link for normally holding said fuse tube in its uppermost position and releasing said fuse tube for downward sliding motion upon rupture of said fuse link, all portions of said tube and closure cap moving downwardly as a unit upon rupture of said fuse link, the means controlled by said fuse link being electrically dead when said fuse tube has slid downwardly.

6. A drop-out fuse device having upper and lower stationary contacts, a downwardly biased fuse tube mounted for both downward and lateral motion, guiding means for slidably guiding said fuse tube, a contact carried by said fuse tube adjacent the upper end thereof and having upwardly slanting surfaces on opposite sides thereof, said upper stationary contact being resilient and having contact surfaces normally engaging the slanting surfaces of the contact of said fuse tube and being spread apart by the contact of said fuse tube and cooperating with said slanting surfaces to produce a cam action urging said fuse tube downwardly, a fuse link within said fuse tube normally electrically connecting the contact of said fuse tube and said lower stationary contact, a stationary latch distinct from said upper stationary contact for holding said fuse tube against lateral motion, and a fuse link extractor biased towards fuse link extracting motion by said fuse tube controlled by said fuse link for normally holding said fuse tube in its uppermost position and releasing said fuse tube for downward sliding motion upon rupture of said fuse link, said fuse link extractor being electrically dead when said fuse tube has slid downwardly.

7. A drop-out fuse device having upper and lower stationary contacts, a downwardly biased

5 fuse tube having an open lower end and having a metal closure cap at its upper end and having a contact adjacent its upper end spaced downwardly from said closure cap, the contact of said fuse tube having slanting faces, said upper stationary contact being resilient and having spaced arms normally engaging the slanting faces of the contact of said fuse tube and cooperating with said slanting faces to produce a downward thrust
10 on said fuse tube, guiding means for slidably guiding said fuse tube, a fuse link within said fuse tube normally electrically connecting said upper and lower stationary contacts and having its upper end clamped by said closure cap and having its lower end projecting from the open end of said fuse tube, and means controlled by said fuse link and normally holding said fuse tube in its uppermost position and releasing said fuse tube upon rupture of said fuse link.

15 8. A drop-out fuse device having upper and lower stationary contacts, a downwardly biased fuse tube having an open lower end and having a metal closure cap at its upper end and having a contact rigidly carried by said fuse tube adjacent its upper end spaced downwardly from

20 said closure cap, the contact of said fuse tube having slanting faces, said upper stationary contact being resilient and having spaced arms normally engaging the slanting faces of the contact of said fuse tube and cooperating with said slanting faces to produce a downward thrust on said

25 fuse tube by means of a cam action with said slanting faces, guiding means for slidably guiding said fuse tube, a fuse link within said fuse tube normally electrically connecting said upper and lower stationary contacts and having its upper end clamped by said closure cap and having its lower end projecting from the open end of

30 said fuse tube, said closure cap locking the upper portion of said fuse link to the upper portion of said fuse tube in spaced relation to the contact carried by the fuse tube, and a fuse link extractor biased towards fuse link extracting motion and controlled by said fuse link and normally holding said fuse tube in its uppermost position

35 and releasing said fuse tube upon rupture of said fuse link.

40 9. A drop-out fuse device having upper and lower stationary contacts, a downwardly biased fuse tube having an open lower end and having a metal closure cap at its upper end and having a contact adjacent its upper end spaced downwardly from said closure cap, said upper stationary contact being resilient and having spaced

45 arms normally engaging the contact of said fuse tube and cooperating with said contact of said fuse tube to produce a downward thrust on said fuse tube, guiding means for slidably guiding said fuse tube, a fuse link within said fuse tube normally electrically connecting said upper and lower stationary contacts and having its upper end clamped by said closure cap and having its lower end projecting from the open end of said fuse tube, means controlled by said fuse link and normally holding said fuse tube in its uppermost position

50 and releasing said fuse tube upon rupture of said fuse link, said guiding means being pivotally mounted, and a latch distinct from said upper stationary contact normally engaging the closure cap of said fuse tube.

55 10. A drop-out fuse device comprising a fuse tube, pivotally mounted guiding means slidably guiding said fuse tube, said fuse tube having an upper contact spaced downwardly from its upper

60 end and having an upper closure cap and having

65 75 7. A drop-out fuse device having upper and lower stationary contacts, a downwardly biased

an open lower end, a fuse link within said fuse tube having its upper end clamped by said closure cap and projecting outwardly from the open lower end of said fuse tube, an upper and a lower stationary contact normally electrically joined by said fuse link, said upper contact engaging the upper contact of said fuse tube, latch means distinct from said upper stationary contact engaging the closure cap of said fuse tube and normally latching said fuse tube against outward motion, and means controlled by said fuse link for normally holding said fuse tube in its uppermost position and releasing said fuse tube upon rupture of said fuse link for downward sliding of said fuse tube.

11. A housed type of drop-out fuse device including a housing, a sleeve pivotally mounted on said housing, a door carried by said sleeve, a fuse tube slidably mounted within said sleeve and having an open lower end and having a closure cap closing its upper end, said fuse tube having an upper contact located below said closure cap, a fuse link within said fuse tube having its upper end clamped by said closure cap and projecting outwardly from the open lower end of said fuse tube, said housing having an upper and a lower stationary contact normally electrically connected by said fuse link, said upper contact being resilient and engaging the upper contact carried by said fuse tube and cooperating with said contact of said fuse tube to provide a downward thrust for said fuse tube, means controlled by said fuse link for normally holding said fuse tube in its uppermost position and releasing said fuse tube for downward sliding motion upon rupture of said fuse link, and a latch distinct from said upper stationary contact carried by said housing for engaging the closure cap of said fuse tube.

12. A housed type of drop-out fuse device including a housing, a sleeve pivotally mounted on said housing, a door carried by said sleeve, a fuse tube slidably mounted within said sleeve and having an open lower end and having a closure cap closing its upper end, said fuse tube having an upper contact spaced downwardly from said closure cap, said housing having an upper and a lower stationary contact, said upper stationary contact normally engaging the contact of said fuse tube, a fuse link within said fuse tube having its upper end clamped by said closure cap and projecting outwardly from the open lower end of said fuse tube and normally electrically connecting said stationary contacts, a latch distinct from said upper stationary contact carried by the housing for engaging the closure cap of said fuse tube, said latch being resilient and urging said fuse tube downwardly, and means controlled by said fuse link for normally holding said fuse tube in its uppermost position, said means releasing said fuse tube for downward sliding motion upon rupture of said fuse link.

13. A housed type of drop-out fuse device including a housing, a sleeve pivotally mounted on said housing, a door carried by said sleeve, a fuse tube slidably mounted within said sleeve and having an open lower end and having a closure cap closing its upper end, said fuse tube having an upper contact located below said closure cap, a fuse link within said fuse tube having its upper end clamped by said closure cap and projecting outwardly from the open lower end of said fuse tube, said housing having an upper and a lower stationary contact normally electrically connected by said fuse link, said upper contact being resili-

ent and engaging the upper contact carried by said fuse tube and cooperating with said contact of said fuse tube to provide a downward thrust for said fuse tube, means controlled by said fuse link for normally holding said fuse tube in its uppermost position and releasing said fuse tube for downward sliding motion upon rupture of said fuse link, and a latch distinct from said upper stationary contact carried by said housing for engaging the closure cap of said fuse tube, said latch exerting a downward pressure on said fuse tube.

14. A housed type of drop-out fuse device including a housing, a sleeve pivotally mounted on said housing, a door carried by said sleeve, a fuse tube slidably mounted within said sleeve and having an open lower end and having a closure cap closing its upper end, said fuse tube having an upper contact located below said closure cap, a fuse link within said fuse tube having its upper end clamped by said closure cap and projecting outwardly from the open lower end of said fuse tube, said housing having an upper and a lower stationary contact normally electrically connected by said fuse link, said upper contact being resilient and engaging the upper contact carried by said fuse tube and cooperating with said contact of said fuse tube to provide a downward thrust for said fuse tube, means controlled by said fuse link for normally holding said fuse tube in its uppermost position, and a latch distinct from said upper stationary contact carried by said housing for engaging the closure cap of said fuse tube, said lower contact being in engagement with said sleeve.

15. A drop-out fuse device having an upper and a lower stationary contact, a fuse tube having an open lower end, guiding means for slidably guiding said fuse tube, said fuse tube being guided for both downward sliding and lateral motion, a contact carried by said fuse tube adjacent the upper end thereof and having slanting surfaces normally engaging the upper stationary contact, said upper stationary contact being resilient and producing a downward thrust on said fuse tube through the agency of said slanting surfaces by means of a cam action with said slanting faces, a fuse link within said fuse tube normally electrically connecting said stationary contacts and projecting outwardly from the open lower end of said fuse tube, a stationary latch distinct from said upper stationary contact for engaging the upper portion of said fuse tube and holding said fuse tube against lateral motion, and a fuse link extractor pivoted intermediate its ends to said fuse tube and having one end detachably engaging supporting means rigid with said guiding means and having the other end secured to the projecting portion of said fuse link, said fuse link extractor normally holding said fuse tube in its uppermost position and releasing said fuse tube upon rupture of said fuse link and detaching itself from the support rigid with said guiding means and being electrically dead when said fuse tube has slid downwardly.

16. A drop-out fuse device having upper and lower stationary contacts, a downwardly biased fuse tube, guiding means for slidably guiding said fuse tube, a contact carried by said fuse tube normally engaging the upper stationary contact and movable away from the upper stationary contact when said fuse tube slides downwardly, a fuse link within said fuse tube normally electrically connecting the contact carried by the fuse tube with the lower stationary contact, a barrier

rigid with said guiding means and extending transversely of said fuse tube, said fuse tube normally projecting below said barrier and slideable downwardly through said barrier, and releasing means normally holding said fuse tube in its uppermost position, said releasing means being located below said barrier and being controlled by said fuse link.

17. A drop-out fuse device having upper and lower stationary contacts, a downwardly biased fuse tube, guiding means for slidably guiding said fuse tube, a contact carried by said fuse tube normally engaging the upper stationary contact and movable away from the upper stationary contact when said fuse tube slides downwardly, a fuse link within said fuse tube normally electrically connecting the contact carried by the fuse tube with the lower stationary contact, a barrier rigid with said guiding means and extending transversely of said fuse tube, said fuse tube normally projecting below said barrier and slideable downwardly through said barrier, and releasing means normally holding said fuse tube in its uppermost position, said releasing means being located below said barrier and being controlled, by said fuse link, said releasing means being carried by said fuse tube and moving downwardly with said fuse tube when said fuse tube slides downwardly upon rupture of said fuse link and being electrically dead when said fuse tube has slid downwardly.

18. A housed type of drop-out fuse device including a housing and a door pivotally mounted on said housing, said housing having upper and lower stationary contacts, a barrier carried by said door and extending transversely of said housing adjacent the lower end of said housing, a fuse tube carried by said door and slideable through said housing and being downwardly biased, a fuse link within said fuse tube normally electrically connecting said stationary contacts, and a fuse link extractor carried by said fuse tube and located below said barrier and controlled by said fuse link, said fuse link extractor normally holding said fuse tube in its uppermost position and releasing said fuse tube upon rupture of said fuse link.

19. A housed type of drop-out fuse device including a channel-shaped housing having an open front and an open lower end, upper and lower stationary contacts located within said housing, a door pivotally mounted on said housing and normally closing the front of said housing, said door having a barrier rigid therewith and located within and extending transversely across the channel-shaped housing above the lower end of said housing, a downwardly biased fuse tube slideable through said barrier, a fuse link within said fuse tube normally electrically connecting said stationary contacts, said fuse tube having a closed upper end and having an open lower end projecting below said barrier when said fuse tube is in its uppermost position,

and a fuse link extracting member carried by the lower portion of said fuse tube and located below said barrier and controlled by said fuse link, said fuse link extracting member normally holding said fuse tube in its uppermost position and releasing said fuse tube upon rupture of said fuse link and moving downwardly with said fuse tube when said fuse tube slides downwardly and being electrically dead when said fuse tube has slid downwardly upon rupture of said fuse link.

20. A housed type of drop-out fuse device including a channel-shaped housing having an open front and an open lower end, upper and lower stationary contacts located within said housing, a door pivotally mounted on said housing and normally closing the front of said housing, said door having a barrier rigid therewith and located within and extending transversely across the channel-shaped housing above the lower end of said housing, a downwardly biased fuse tube slideable through said barrier, a fuse link within said fuse tube normally electrically connecting said stationary contacts, said fuse tube having a closed upper end and having an open lower end projecting below said barrier when said fuse tube is in its uppermost position, and a fuse link extracting member carried by the lower portion of said fuse tube and located below said barrier and controlled by said fuse link, said barrier being located between said fuse link extracting member and the lower stationary contact, said fuse link extracting member normally holding said fuse tube in its uppermost position and releasing said fuse tube upon rupture of said fuse link and moving downwardly with said fuse tube when said fuse tube slides downwardly and being electrically dead when said fuse tube has slid downwardly upon rupture of said fuse link.

21. A drop-out fuse device having upper and lower stationary contacts, a downwardly biased fuse tube mounted for both downward sliding and lateral motion, guiding means for slidably guiding said fuse tube, a contact carried by said fuse tube adjacent the upper end thereof and cooperating with said upper stationary contact, said upper stationary contact being resilient and having slanting contacting surfaces engaging the contact of said fuse tube and producing a downward thrust on said fuse tube due to the cam action between said slanting faces and the contact of said fuse tube, a stationary latch distinct from said upper stationary contact for engaging the upper portion of said fuse tube and holding said fuse tube against lateral motion, and a fuse link extractor biased towards fuse link extracting motion and controlled by said fuse link and normally holding said fuse tube in its uppermost position and releasing said fuse tube upon rupture of said fuse link, said fuse link extractor being electrically dead when said fuse tube has slid downwardly.
